REFRIGERATING APPARATUS

William W. Higham, Detroit, Mich., assignor to
 Universal Cooler Corporation, Detroit, Mich., a
 corporation of Michigan

Application June 2, 1939, Serial No. 276,941

10 Claims. (Cl. 62—95)

This invention relates to refrigerating apparatus and has to do particularly with a heat absorbing or cooling structure, which structure includes an evaporator. The invention is devoted particularly to an arrangement for the cooling or refrigeration of a plurality of compartments and wherein it is feasible to obtain different temperatures in the compartments.

In accordance with this invention a structure for the refrigerating units preferably takes the form of that in the Higham and Morse Patent No. 2,138,525 of November 29, 1938, wherein a long strip of metal, which may be extruded, is fashioned into coils. As set forth in said patent, such a strip may be of metal capable of being extruded and worked, such, for example, as an aluminum or aluminum alloy, or other metals. The object of the present invention is to provide an evaporator of this nature, which may be disposed and arranged to cool one compartment directly and to also cool one or more secondary refrigerating mediums which may have circulatory paths of movement through one or more other cooling elements disposed in one or more other compartments. Where a plurality of secondary cooling or refrigerating mediums are used, the arrangement may be such that one medium is cooled more than the other, to the end that different temperatures may be maintained in different compartments. These and other objects will become more apparent as the detailed description progresses in conjunction with the accompanying drawings.

Structures for carrying out the invention are shown in the drawings wherein:

Fig. 1 is an elevational view of a refrigerator cabinet showing the cooling arrangement and illustrating the cabinet with the door open.

Fig. 2 is an enlarged view taken substantially on line 2—2 of Fig. 1.

Fig. 3 is an enlarged sectional detail illustrating the arrangement at one end of the evaporator.

Fig. 4 is a sectional view taken substantially on line 4—4 of Fig. 3.

Fig. 5 is a perspective view of the evaporator unit.

Fig. 6 is a view with some parts in section illustrating a modified form.

Fig. 7 is a view similar to Fig. 6 illustrating a further modified form.

In Fig. 1 the cabinet is more or less diagrammatically illustrated at 1 having the usual door 2 and a lower compartment 3 which may house the mechanism such as the compressor. Above the compartment 3 is the refrigerating space shown

herein as being divided into three compartments 4, 5, and 6 by partitions 7 and 8. A tube 9 may extend from compartment 4 downwardly to the compartment 3 for conducting liquid refrigerant, while a tube 10 is for carrying the evaporated refrigerant in gaseous form from the evaporator back to the compressor in the compartment 3.

The evaporator is generally shown in Fig. 5, and it is formed by a plurality of coils or runs of a strip of metal, the cross sectional shape of which is illustrated in Fig. 3. This strip of metal comprises a body portion 12 with flanges 13 and 14, and the body portion has three hollow or tube-like formations illustrated at 16, 17 and 18. The evaporator is formed by successive coils or runs indicated at 20, the runs being fashioned back and forth. The entrance end, where the tube 9 connects, has the flanges 13 and 14 removed, and the strip is divided or split so that the central form 17 may be turned upwardly and connected with tube 9. A controlling device for controlling flow of refrigerant into the evaporator, such as an expansion valve or the like is illustrated at 21. The two tubular forms 16 and 18 may be turned downwardly. The first run extends for a suitable distance with the flanges intact, and then the flanges are removed for a portion of the length, and the stock is fashioned or bent through 180° as shown at 23. The strip then returns along side of the first run where the flanges are again removed and the strip fashioned through 180° to form another bend or bight 23 connecting into the third run or coil, and this continues until an evaporator of a suitable size is provided. At the outlet end the central portion 17 is connected to the return line 10, while tubular portions 16 and 18 may be turned downwardly, this being accomplished by removing the flanges and splitting the strip, as illustrated. The run or coils are arranged so that the flanges and strip cooperate to form a substantially solid wall, as illustrated in Fig. 5, and to this end the meeting flanges of the successive runs may be secured together as illustrated in Fig. 3. In this connection a strip of U-shape in cross section is illustrated at 24 and may be fashioned over the dovetail shaped ribs 25 on the edges of the flanges. In this manner a solid wall is formed and trays of water or food stuffs may be placed upon the wall provided by the runs 20.

Thus, as illustrated in Fig. 2, liquid refrigerant enters the central tubular form 17, passes through

the successive runs and then passes out through the suction line 10.

- The compartment 5 may be provided with a cooling element generally illustrated at 27, and this cooling element may be formed also in accordance with the above mentioned Higham and Morse patent comprising a strip which may be extruded, having a tubular portion 28 and flanges 29 which may be secured together at their edges.
- 10 The flanges are removed from the strip where the tube is to be given a reverse bend as shown at 30. Tube lines 31 and 32 connect the passageway 18 in the evaporator to the tube 28 of the cooling unit 27. These tubes may be secured to
- 15 the portions 18 and 28 in any suitable manner, preferably by a fused metal connection which may be in the nature of a soldering operation, brazing operation or weld, the connections being illustrated at 34. The compartment 6 has a cooling unit 36 which, as shown, is of the same structure as the cooling unit 27, and it is connected by the tube lines 37 and 38 to the tube formation 16. The connections are illustrated again at 34.
- 20 25 A suitable fluid heat-transferring medium is placed in the interconnecting tubular formations 18, 28, 31 and 32, and this medium may advantageously be a suitable liquid which substantially fills these passageways. Likewise, a suitable fluid heat transfer medium is placed in the cooling unit 36 and advantageously preferably fills the tube connections 37 and 38 and the tubular structure 16.

In the operation of the device liquid refrigerant 35 is passed to the evaporator through the control element 21 and this expands and evaporates into gaseous form in the passageway 17, and is removed in gaseous form through the suction line 10. This cools the compartment 4. At the same 40 time the heat transfer fluid for the compartment 5 is cooled by the transfer of heat from the refrigerant in the passageways 17 to the transfer medium in the tubular formation 18. This heat transfer medium may be caused to circulate by 45 thermosiphon action, the medium being cooled in the upper portion of its circulatory path and flowing downwardly to the compartment where it is warmed by the absorption of heat. Similarly, the heat transfer medium in the secondary 50 system, including the cooling unit 36, cools the lower compartment with the arrangement shown. The two compartments 5 and 6 may be cooled to about the same temperature, inasmuch as the evaporating refrigerant is passed through the 55 central tubular formation 17, thus substantially equally cooling the medium in the formations 16 and 18. The compartment 4, of course, may be maintained at a lower temperature than compartments 5 or 6. Even in this arrangement, 60 compartments 5 and 6 may be varied as to their refrigeration by varying the size of the cooling units therein or by restricting the flow of the cooling medium.

A modified arrangement is shown in Fig. 6 65 wherein the evaporator and cooling units are of the same structure as that just described, and the same reference characters are applied to corresponding parts. This avoids the necessity of duplicate description. In this case, however, the 70 refrigerant passes through one of the end tubular formations in the strip which forms the evaporator, as for example, the passageway 18. One of the secondary cooling units, as for example, the cooling unit in the compartment 5, is connected 75 to the central conduit formation 17 by its tubes

31 and 32; whereas the other secondary cooling unit, that is the one for the lower compartment 6, has its tube lines 37 and 38 connected into the opposite end conduit formation 16. In this way, the cooling medium in the secondary unit 5 for cooling the compartment 5, being next adjacent the refrigerant, is cooled more than the cooling medium in the secondary unit for the compartment 6. Accordingly, the compartment 5 may be held at a lower temperature than the compartment 6. Additional variation may be obtained by varying the size or capacity of the secondary units and the flow of the heat transfer medium.

In Fig. 7 a system is shown where there is 15 only one secondary cooling unit and corresponding parts in this view bear the same reference characters as those which have been heretofore used. The evaporator in this form comprises a strip 45 with only two tubular formations therein 46 and 47. The strip, however, may otherwise be similar to the strip shown in Fig. 3, and the evaporator may be constructed along the lines of that shown in Fig. 5. The refrigerant line 9 connects to the tubular form 46, and the suction 25 line 10 connects to the other end of the tubular form 46. The cooling unit 48 is connected to the tubular form or passageway 47 through the tubes or pipes 49 and 50. Thus refrigerant cools the upper compartment 4a directly and cools the 30 lower compartment 5a through the means of a fluid transfer medium in the secondary cooling unit and circulatory path, in the manner as above described. The relative sizes of the several compartments, as illustrated herein, are of no particular consequence, as the sizes of the compartments 35 may be varied.

The secondary cooling systems may be assembled and sealed with a primary cooling system, and each secondary system may then be charged 40 with its cooling fluid. This may be done by means of a charging valve 51.

I claim:

1. In a refrigerating system, the combination of a strip of metal having a plurality of passages 45 running lengthwise therethrough in heat exchange relationship substantially from end to end of the strip, said strip being fashioned into runs or coils to form a primary cooling unit, means for introducing condensed refrigerant into one of the passages and for conducting evaporated refrigerant from said passage, and a secondary cooling unit having a passage therein and connected to one of said plurality of passages in the said strip and forming therewith a 50 closed circuitous path for a fluid cooling medium.

2. In a refrigerating system, the combination of an integral strip of metal having a plurality of passages running lengthwise therethrough in heat exchange relationship substantially from 60 end to end of the strip, said strip being fashioned into runs or coils to form a primary cooling element, means for conducting condensed refrigerant into one of the passages and for conducting evaporated refrigerant from said passage, a 65 secondary cooling unit having a passage therein, and conduits connecting the passage of the secondary cooling unit to one of the other passages in said integral strip to form therewith a closed circuitous path for a fluid cooling medium.

3. In a refrigerating system, the combination of an integral strip of metal having a plurality of passages running lengthwise therethrough in heat exchange relationship substantially from 75

- end to end of the strip, said strip being fashioned into runs or coils to form a primary cooling element, means for conducting condensed refrigerant into one of the passages and for conducting evaporated refrigerant from said passage, a secondary cooling unit having a passage therein, and conduits connecting the passage of the secondary cooling unit to one of the other passages in said integral strip to form therewith a closed circuitous path for a fluid cooling medium, said secondary cooling unit being located at an elevation lower than the primary cooling unit for the circulation of the fluid cooling medium by thermosiphon action.
4. In a refrigerating system, the combination of a strip of extruded metal having a plurality of passageways integrally formed therewith and running lengthwise therethrough in heat exchange relationship substantially from end to end of the strip, said strip being fashioned into runs or coils to form a primary cooling element, means for conducting condensed refrigerant into one of the passages and for conducting evaporated refrigerant from said passage, a secondary cooling unit having a passage therein, and conduits connecting the passage of the secondary cooling unit to one of the other passages in said integral strip to form therewith a closed circuitous path for a fluid cooling medium.
5. In a refrigerating system, the combination of a plurality of chambers to be refrigerated, a strip of metal having a plurality of passages running lengthwise therethrough in heat exchange relationship substantially from end to end of the strip, said strip of metal being fashioned into coils or runs to form a primary cooling unit disposed in one of the chambers, means for introducing compressed refrigerant into one of the passages and for conducting evaporated refrigerant from said passage, a secondary cooling unit in another of said chambers and having a passage therein, and conduit means connecting the secondary cooling unit to one of the said plurality of passages in said strip to form therewith a closed circuitous path for a cooling medium.
6. In a refrigerating system, the combination of three chambers to be refrigerated, a strip of metal having three passages running lengthwise therethrough, said strip of metal being fashioned into runs or coils to form a primary cooling unit and located in one of the chambers, means for introducing compressed refrigerant into one of the passages and for conducting evaporated refrigerant from said passage, and two secondary cooling units each having a passage therein and located respectively in the other two chambers and each connected with one of the other passages in said strip to form therewith closed circuitous paths, each for a fluid cooling medium.
7. In a refrigerating system, the combination of three chambers to be refrigerated, a strip of metal having three passages running lengthwise therethrough, said strip of metal being fashioned into runs or coils to form a primary cooling unit and located in one of the chambers, means for introducing compressed refrigerant into one of the passages and for conducting evaporated refrigerant from said passage, and two secondary cooling units each having a passage therein and
- located respectively in the other two chambers and each connected with one of the other passages in said strip to form therewith closed circuitous paths, each for a fluid cooling medium, the chambers containing the secondary cooling units being located below the chamber containing the primary unit for the circuitous flow of the cooling mediums by thermosiphon action.
8. In a refrigerating system, the combination of three chambers to be refrigerated, a strip of metal having three passages running lengthwise therethrough, said strip of metal being fashioned into runs or coils to form a primary cooling unit and located in one of the chambers, said three passageways being disposed in a row transversely of the strip, means for introducing compressed refrigerant into the center one of said passages and for conducting evaporated refrigerant therefrom, a secondary cooling unit in each of the other two chambers, and conduit means connecting each of the secondary cooling units respectively to the two outside passageways in said strip to form therewith closed circuitous paths for a fluid cooling medium for each secondary unit whereby the cooling action on the cooling fluids for the secondary units is substantially the same.
9. In a refrigerating system, the combination of three chambers to be refrigerated, a strip of metal having three passages running lengthwise therethrough, said strip of metal being fashioned into runs or coils to form a primary cooling unit and located in one of the chambers, said passages being lined up in a row transversely of the strip, means for introducing compressed refrigerant into one of the outside passages and for conducting evaporated refrigerant therefrom, two secondary cooling units, one located in each of the other of said chambers and having passages therein, means connecting one of the secondary cooling units to the middle passage in said strip to form therewith a circuitous path for a fluid cooling medium, and means for connecting the other secondary cooling unit to the opposite outside passageway in said strip to form therewith a closed circuitous path for a fluid cooling medium whereby there is a greater cooling action on the cooling medium for one of the secondary cooling units than on the other.
10. In a refrigerating system, the combination of a cabinet having three superposed chambers to be refrigerated, a strip of metal having three passageways running lengthwise therethrough, said strip of metal being fashioned into runs or coils to form a primary cooling unit and located in the upper chamber, means for introducing compressed refrigerant into one of the passages and for conducting evaporated refrigerant therefrom, a secondary cooling unit located in each of the other chambers, and conduit means connecting each secondary cooling unit with one of the other of said passages in the strip to form therewith a closed circuitous path for a fluid cooling medium for each of the said secondary cooling units, the cooling mediums for the secondary units being refrigerated by the said refrigerant and circulating in the respective paths by thermosiphon action.
